UNITED STATES PATENT OFFICE.

WILLIAM H. O'BRIEN, OF AKRON, OHIO.

DESIGN FOR A PRINTER'S QUOIN.

SPECIFICATION forming part of Design No. 29,234, dated August 16, 1898.

Application filed July 9, 1898. Serial No. 685,529. Term of patent 3½ years.

To all whom it may concern:

Be it known that I, WILLIAM H. O'BRIEN, a citizen of the United States, residing at Akron, in the county of Summit and State of Ohio, have invented and produced a new and original Design for Printers' Quoins, of which the following is a specification, reference being had to the accompanying drawing, forming a part thereof, in which is shown a perspective view of a printer's quoins embodying the features of my design.

In detail the design consists of a base member A, side members B, connected by a cross-bar C, and an apex D, the sides, connecting-bar, base, and apex combinedly forming two approximately-triangular spaces E and E'.

A longitudinal rib F is formed at the inner face of the side and base members of the quoins, and upon the outer face of the sides and the apex members teeth G appear.

The leading feature of the design is a quoins which is of substantially triangular shape, its outer side edges having interruptions corresponding to teeth.

I claim—

The design for a printer's quoins, as herein shown and described.

WILLIAM H. O'BRIEN.
